ELECTRICAL SWITCH BOX

Stephen A. George, Johnstown, Pa., assignor to
 Stephen A. George Company, Johnstown, Pa.,
 a corporation of Pennsylvania

Application February 14, 1951, Serial No. 210,961

3 Claims. (Cl. 200—114)

1

This invention relates to electrical switch boxes, and more particularly to electric switch boxes of the type having contacts on the cover which mate with corresponding contacts in the box when the cover is closed and having means on the cover for receiving a replaceable fuse.

It is the principal object of this invention to provide a switch box for interrupting relatively large currents without danger to the operator of the switch.

It is another object of this invention to provide a switch box incorporating a replaceable fuse which is so arranged that there is no danger of shock to the person who is removing and replacing a fuse in the device.

It is a further object of the invention to provide a switch box, the mating contacts of which make a sure and positive connection.

It is a further object of this invention to provide a switch box, the cover of which serves also as the movable arm of the switch.

It is a further object of this invention to provide a switch box having a hinged cover, the box and the cover cooperating to completely enclose the parts of the switch and protect it from damage and to protect persons from contact with the charged parts therein.

The switch box of this invention is characterized by an improved contact finger which ensures the provision of a non-arching switch.

Also, the present invention embodies certain new and useful improvements over the electric switch box disclosed in my copending application Serial No. 36,137, filed June 30, 1948, now abandoned, entitled Electrical Switch Boxes, and of which application this present one is a continuation-in-part.

These and other objects of the invention will be apparent to those skilled in the art from a perusal of the following detailed description taken in conjunction with the accompanying drawings wherein:

Figure 1 is a front elevational view of a presently preferred embodiment of the invention showing the box closed;

Figure 2 is a sectional view taken substantially on the line 2—2 of Figure 1 showing the arrangement of parts in the interior of the device when the cover is closed;

Figure 3 is a front elevational view of the box with the cover open and revealing the components in the box and on the cover;

Figure 4 is a sectional view of the same taken approximately on the line 4—4 of Figure 3;

Figure 5 is a view similar to Figure 4 and illus-

2

trating an alternate form of spring mounted contact finger;

Figure 6 is a view similar to Figure 2 and further illustrating the alternate form of spring mounted contact finger; and

Figure 7 is an exploded view of the spring mounted contact finger shown in Figures 5 and 6.

Referring now in detail to the drawings, it will be seen that throughout Figures 1 through 6 there is shown a box designated generally by the numeral 10, having a rear wall 11, sides 12, a top wall 13 and a bottom wall 14.

The wall 11 of the box is secured to a mounting plate 15; and the wall 13 of the box is provided with a perforation and inset grommet bushing 16 through which is trained an electric wire 22.

An insulating block 17 is secured to the wall 11, internally of the box adjacent the upper end 13, through suitable fastening means 18. A stationary contact plate 20 is mounted on the insulating block 17 by fastening means 21. The aforementioned wire 22, of the circuit to be interrupted, is, as previously stated, trained through the grommet 16 and at one end is securely connected to the stationary contact plate 20, as shown.

An insulating block 25 is secured to the wall 11 of the box adjacent the bottom wall 14 thereof by fastening means 26. Secured to the surface 30 of the insulating block 25 by means of a bracket 33 is one end of a coil spring 28. Spring 28 at its free end is provided with a contact 30. The other wire 32 of the circuit to be interrupted has an end portion thereof trained through an insulating grommet bushing 31 mounted on one side wall 12 of the box, and the wire is secured electrically to the mounting bracket 33 holding the spring 28 to the insulating block 25.

For the box 10 there is provided a cover designated generally by the reference numeral 40. Cover 40 is hingedly connected with the wall 14 of box 10, as indicated generally at 41. Cover 40 includes a base member 42, an end member 43 and side members or flanges 44. The end member 43 is cut away as at 45 to accommodate the grommet bushing 16 when the box is in the fully closed position of Figures 1, 2 and 6.

It will be noted that the side members 44 and end member 43 of cover 40 extend around the sides 12 and end wall 13 of box 10 when the cover is in closed position. Thus, by this construction a metallic shield is effected around the box 10 which serves to enclose the interior of the box even when the cover 40 is moved to a partially open position. In this way, arcs which might

occur within the box when the contacts are broken, are effectively contained within the box and injury to the operator of the switch is precluded.

To facilitate manipulation of cover 40, the same is provided with a conveniently disposed handle 67. Also suitable detent means 68 is provided for releasably retaining the cover 40 in its normally closed position.

Suitably secured to the cover member 42, by fastening means 47, is a large insulating block 46. Secured to the insulating block 46 at the end thereof near the hinge 41 is a stationary contact member 50 equipped with a fuse clamp 53. Also secured to the insulating block 46 is a connecting plate 64 to which is rigidly secured a second fuse clamp 69. The fuse clamps 53 and 69 support a conventional removable fuse link 70 as shown.

A salient feature of this invention is the provision of a contact finger carried by the cover 40 for coaction with the contact plate 20 mounted, as before described, in the box 10.

In the form of the invention shown in Figures 1 to 4 inclusive, the mentioned contact finger comprises a single flexible strip 62 which at one end is positively secured to the aforementioned connecting plate 64. To the free end of the strip 62 is secured a contact knob 61 of conductive material, such as copper. The knob 61 is shaped to provide a substantially spherical contact surface for positive sliding contact with the plate 20 incidental to the movement of the contact knob 61 into and out of electrical engagement with the plate 20 in response to the swinging of the cover 40 into and out of closing position relative to the box 10. By providing such sliding action incidental to the movement of the contact knob 61 into and out of electrical engagement with the stationary contact plate 20, not only is good electrical contact ensured but the possibility of arcing resulting from such engagement and disengagement of knob 61 and plate 20 is reduced to a minimum.

As is believed to be apparent, the flexible strip 62 of contact finger 60 flexes about its mounted end 63, and to restrain the outward movement of the contact finger without interfering with the desired flexing of the strip 62, there is provided a limiting bolt 66 that extends through an opening provided therefor in the strip 62, and is anchored at one end to the insulating block 46.

As an alternate to the contact finger 60 just described in detail, there may be employed, with even more desirable results, a contact finger of the type detailed in Figure 7, and the application of which is shown in Figures 5 and 6. As shown in Figure 7, this alternate form of contact finger, designated generally by the reference numeral 71, comprises a resilient strip 72 and a plurality of relatively thin strips 73, of conductive material providing a laminated strip corresponding substantially to the strip 62 of the aforementioned contact finger 60. Strips 72 and 73 are secured in superimposed facial contact through the medium of bolts 74 and 75. The strips 72 and 73 are suitably apertured to accommodate the bolts 74, 75 with bolt 74 additionally functioning to anchor the laminated strips to the connecting plate 64, and the bolt 75 additionally functioning to secure, in the assembly, the contact knob 76.

Another salient feature of the contact finger 71 is the contact knob 76. This knob 76 is fabricated from carbon and is suitably formed, as is

shown, for threaded reception of the bolt 75. The knob 76, also like to the knob 61, provides a substantially spherical or working contact surface for sliding movement relative to the stationary contact plate 20 incidental to the movement of the knob 76 into and out of electrical contact with the stationary contact plate 20.

It has been found in actual practice that by forming the contact finger 71 of laminated strips of conductive material, a more desirable tension for the finger is obtained and also better current contact between the finger and the stationary contact plate 20 results. Also, by having the knob 76 fabricated from carbon, arcing incident to the engaging and disengaging of knob 76 and plate 20 is wholly eliminated.

In actual use, the switch box will normally be mounted on a wall or other upright surface with the hinge 41 at the lower end of the box as shown in the drawings. It is desirable to mount the box 10 at such a height that it may be reached, and yet be high enough so that it will not be accidentally encountered by a person in the vicinity. It will be further noted that when so mounted the cover 40 swings downwardly to open position.

It will be apparent that when the cover 40 is in the closed position shown in Figures 2 and 6, the spring contact finger (60 or 71 as the case may be), is in electrical engagement with the stationary contact plate 20, and contact plate 50 is in electrical engagement with spring biased contact 30. To open the box all that is necessary is for the operator, grasping the handle 67, to exert a pull on the handle whereby the cover 40 is released to swing to open position. As the cover swings to such open position the contact knob (60 or 71 as the case may be), with a sliding action over the surface of the contact plate 20, moves out of engagement with the latter for interrupting the circuit. With the cover in the open position, access is then readily had to the fuse link 70 for removing or replacing the same as necessary or desired, without the slightest danger of electrical shock.

In connection with the foregoing it will be noted that the end of the cover 40 containing the contact finger (60 or 71 as the case may be), is enclosed by the side walls 44 and end member 43. The walls 44 and end member 43 thus serve to maintain the interior of the box 10 completely enclosed until the contact finger (60 or 71 as the case may be) has made contact with, or broken contact with, the contact plate 20. Accordingly, any arcing attendant upon operation of the switch is effectively contained within the box and thereby the operator is completely shielded from the arcing. In this connection, however, it may be further noted that by providing the contact finger (60 or 71 as the case may be) with a contact knob having a spherical surface in sliding contact with the plate 20, the possibility of such arcing is reduced to a minimum, and when the contact knob of the finger is fabricated from carbon, as in the case of knob 76, the possibility of such arcing is wholly eliminated.

From the foregoing then it will be seen that an electrical switch box embodying the features of this invention possesses to a material degree salutary high characteristics of safety, ease of operation, and economy of manufacture and maintenance.

While the invention has been described in detail in its presently preferred embodiments, it will, of course, be understood that such has been done for purposes of illustration and not by way of

limitation, and, therefore, only such limitations are to be imposed thereon as may reasonably come within the scope of the appended claims, as for example, it will also be readily appreciated that a resilient contact corresponding to either contact 60 or contact 71 may be substituted for the contact 50, in which event the two contacts carried by the cover 49 would then be equipped with a knob having a peripheral surface for sliding movement over the surfaces of the co-operating contacts mounted in the switch box incidental to the movement of the contacts into and out of circuit closing position.

What I claim is:

1. A switch mechanism of the kind described comprising a box, a cover hinged on the box, spaced contacts within the box adjacent the upper and lower ends of the latter, and complementary contacts on the cover of which one consists of a spring arm with a terminal spherical contact foot, the box-carried contact complementary to the last said cover-carried contact being in the form of a plate so that when the cover is opened, the foot both rolls and slides on the plate and leaves the latter at a point remote from that at which it rests when the cover is closed.

2. A switch mechanism of the kind described comprising a box, a cover hinged on the box, spaced contacts within the box adjacent the upper and lower ends of the latter, and complementary contacts on the cover of which one consists of a spring arm with a terminal spherical contact foot, the box-carried contact complementary to the last said cover-carried contact be-

ing in the form of a plate so that when the cover is opened, the foot both rolls and slides on the plate and leaves the latter at a point remote from that at which it rests when the cover is closed, and an electrical fuse providing electrical continuity between the cover-carried contacts.

3. A switch mechanism of the kind described comprising a box, a cover hinged on the box, spaced contacts within the box adjacent the upper and lower ends of the latter, and complementary contacts on the cover of which one consists of a spring arm with a terminal spherical contact foot, the box-carried contact complementary to the last said cover-carried contact being in the form of a plate so that when the cover is opened, the foot both rolls and slides on the plate and leaves the latter at a point remote from that at which it rests when the cover is closed, and the other cover-carried and box-carried contacts consisting of a plate on the one and a spring biased contact on the other provided with a terminal bearing disc bearing on said plate when the cover is closed.
